UNITED STATES PATENT OFFICE.

HARRY S. HART, OF CHICAGO, ILLINOIS.

DUMP-CAR CONSTRUCTION.

1,273,853.

Specification of Letters Patent. Patented July 30, 1918.

Application filed May 24, 1918. Serial No. 236,275.

To all whom it may concern:

Be it known that I, HARRY S. HART, a citizen of the United States, residing at Chicago, in the county of Cook and State 5 of Illinois, have invented certain new and useful Improvements in Dump-Car Construction, of which the following is a specification.

This invention relates to freight cars of 10 the type commonly known as hopper cars which are used very largely for the transportation of coal or like dumpable material, and has among its objects the improvement of this type of car so as to greatly increase 15 the load carrying capacity of the car without changing its overall dimensions and to provide such a car from which the load may be more quickly discharged with a minimum amount of labor, the car being practically 20 self clearing. With these and other objects, which will hereinafter be pointed out, the invention consists in the combinations and details described in the following specifications and claims.

25 The invention is illustrated on the accompanying sheets of drawings, in which—

Figure 1 is a fragmentary side elevation of a dump car constructed in accordance with my invention;

30 Fig. 2 is a longitudinal sectional view of the same;

Fig. 3 is a transverse sectional view of the dump car taken intermediate the trucks;

Fig. 4 is a transverse sectional view of the 35 dump car taken over the trucks; and

Fig. 5 is a fragmentary plan view of the dump car.

Prior to my invention it has been customary to build hopper cars for the transportation 40 of coal and the like commodities having inclined end portions over the trucks discharging the load through the center of the car by means of cross hoppers or longitudinal hoppers provided with suitable doors.

45 These prior constructions are well known and require no particular description for an understanding thereof. Owing to the location of the inclined end portions over the trucks that portion of the cars at the 50 ends is largely useless for load carrying so that any attempt to increase the capacity of these cars has necessarily been by lengthening the car or by increasing its height, while the discharge of the load through the 55 cross hoppers is difficult even where special unloading stations are provided owing to

the necessarily restricted door opening provided in the cross hoppers. While longitudinal hoppers have also been provided in cars of this type for discharging the load 60 at the side so as to make the unloading easier, attempts to apply this principle to the car throughout its length have resulted in a greatly decreased load carrying capacity. By my present invention I entirely 65 overcome the difficulties hitherto experienced in this type of car, making it possible to carry in a car of the same length an increased load of approximately 20%, at the same time making it possible to discharge 70 the load at a greatly reduced expenditure of time and labor.

The body 10 of this dump car, which is carried upon trucks including wheels 11 at each end of the car, comprises sides 12, ends 75 13 and a floor 14.

The floor 14 consists of downwardly and outwardly sloping portions 18 shown over the trucks extending from a point adjacent the center sill toward the sides of the car. 80 Between the trucks the floor consists of downwardly and outwardly extending sections 21 secured along their inner edges to the center sill 20, preferably at or near the lower edge thereof, the floor portions 21 being at a lower level than the floor portions 18. In order that the car may be self clearing in unloading, I have shown in the present embodiment of my invention the floor sections 18 over the trucks extending upwardly to a point over the center sill so as to form an A-shaped apex 15 as a continuation of the floor sections. Between the trucks I have shown an A-shaped portion 16 mounted over the center sill so as to form 95 shedding surfaces coöoperating with the floor sections 21. It will be understood, however, that these A-shaped portions may be unnecessary in the event that a narrow center sill is used. The upper and lower floor sections at the ends and intermediate portion of the car respectively may be connected by a floor member 17 sloping downwardly toward the longitudinal center of the car. Suitable means may be provided for closing 100 the space between the outer edges of the sloping floor sections and the sides of the car, through which space the load is dumped. In the present embodiment of my invention I have shown side dump doors 19, which 110 are pivotally connected at the lower edges of the sides 12, extending downwardly and

inwardly with respect to the center of the car to meet the outer edges of the A-shaped portions 18 which are over the trucks. Similar doors 22 are pivotally connected to the lower edges of the sides 12 between the trucks, these doors 22 being of greater length than the doors 19, so as to meet the outer edges of the sloping members 21. By thus providing a car having load carrying capacity throughout its length with a stationary floor of the construction above described, I am enabled to provide a hopper car of maximum load carrying capacity for any given length and width, at the same time making the car self-clearing owing to the arrangement of the inclined surfaces in the car with relation to the dumping doors. The side dump doors 19 and 22 may be provided with any suitable operating mechanism. In this car I prefer to have the draft and center sills in alignment with each other.

By means of the construction above described the effective depth of the car is greatly increased not only over the trucks but intermediate the same, the effective capacity of the car being greatly increased without increasing the overall height, length or width of the car. The side dump doors and the floor of the car are so arranged and coöperate with each other in a novel manner to meet successfully all requirements.

It is my intention to cover all modifications of my invention falling within the spirit and scope of the following claims.

I claim:

1. A car having side and end portions, a center sill, a stationary floor extending from end to end of the car and composed of fixed portions sloping downwardly and outwardly from the center sill toward the sides

of the car, the floor portions over the trucks being at a higher level than the floor portions between the trucks, the car sides comprising upper stationary portions, and doors 45 extending between the stationary portion of the sides and the outer edges of the floor.

2. A car having side and end portions and a center sill, a stationary floor extending from end to end of the car, said floor being 50 composed of fixed portions sloping downwardly and outwardly from center sill toward the sides of the car, the floor portions between the trucks being at a lower level than the floor portions over the trucks, and 55 comprising fixed sloping portions attached at their inner edges at or near the center sill.

3. A car of the class described having sides, ends, and a stationary floor extending from end to end of the car, the floor comprising end portions and intermediate portions, the intermediate portions extending between the trucks only and being at a lower level than the end portions, the end portions and intermediate portions being composed of fixed sections sloping downwardly 60 and outwardly toward the sides of the car.

4. A car of the class described, having a center sill, a stationary floor extending from end to end of the car, said floor being composed of members sloping downwardly and outwardly from the center sill toward the sides of the car, the portion of the floor between the trucks being at a lower level than the portion over the trucks, and downwardly sloping members connecting the floor portions over the trucks with the floor portions between the trucks. 75

Signed at Chicago, Illinois, this 15th day of May, 1918.

HARRY S. HART.
